UNITED STATES PATENT OFFICE.

JOHN D. MOORE, OF NEW YORK, AND FRED M. MARTIN, OF BROOKLYN, NEW YORK; SAID MOORE ASSIGNOR TO THE CLAYTON FIRE EXTINGUISHING & DISINFECTING COMPANY, A CORPORATION OF WEST VIRGINIA.

METHOD OF EXTINGUISHING FIRES.

SPECIFICATION forming part of Letters Patent No. 700,967, dated May 27, 1902.

Application filed May 22, 1901. Serial No. 61,343. (No model.)

To all whom it may concern:

Be it known that we, JOHN D. MOORE, of the borough of Manhattan, and FRED M. MARTIN, of the borough of Brooklyn, in the city and 5 State of New York, citizens of the United States, have invented certain new and useful Improvements in Methods of Extinguishing Fires, of which the following is a specification, reference being had to the drawings accompanying and forming a part of the same.

Our present invention pertains to the general plan of charging closed compartments with gas for the purpose of fumigating or preventing or extinguishing fires therein, disclosed in patents to Thomas A Clayton, No. 633,807, dated September 26, 1899, and No. 661,497, dated November 13, 1900, and is an improvement on such method especially designed for use in extinguishing fires in certain kinds of merchandise which when once started are so persistent as to defy all ordinary methods for their complete extinction.

It has been found that no ordinary combustibles can be ignited in a closed chamber 25 the atmosphere of which contains a certain proportion of sulfur-dioxide gas, varying from two or three up to fifteen per cent. It has also been found that a great majority of combustible materials such as usually constitute 30 the cargoes of ships when completely ignited and in an advanced stage of combustion may be very quickly extinguished by charging the compartment in which they are contained with a similar atmosphere; but attempts to 35 extinguish in this way a fire which has once fairly started in a mass or bale of cotton have resulted in failure. The practical and immediate reason for such failure is the fact that it is not feasible or practicable to charge 40 a compartment, such as a section of a ship's hold or a room in a warehouse, with an atmosphere which is an absolute non-supporter of combustion, and it appears that an atmosphere containing the highest proportion of 45 sulfur dioxide which it is practical to produce is not alone sufficient to extinguish fires of the refractory nature referred to. In working on this problem—that is to say, extin-

guishing a fire which has once gained headway in a mass of cotton—we made the discovery, on which our present application is based, that if a sufficient volume of mixed air and sulfur-dioxide gas be forced into a compartment which is closed substantially air-tight to produce and maintain therein a pressure even slightly above that of the atmosphere the presence of a comparatively small proportion of sulfur dioxide—say from eight to fifteen per cent.—will almost immediately extinguish a fire in a mass of baled cotton 60 which may have gained such headway as would persist even were the bales immersed completely for a considerable time in water. This method of extinguishing fires—to wit, by producing and maintaining under pressure in an air-tight compartment in which the ignited combustibles are stored an atmosphere containing such a gas as sulfur dioxide—is the only practicable one, so far as we have any information, for extinguishing a cotton 65 fire, one of the most dangerous and destructive of all that occur on shipboard and in storage-warehouses.

The method may be carried out in many ways and by the use of widely-different forms 75 of apparatus; but in the accompanying drawings we have illustrated a simple and efficient apparatus for the purpose.

A designates a retort or generator by which a large volume of sulfur-dioxide gas may be 80 produced. Any of the ordinary devices commonly used for this purpose may be employed, though we prefer the form which we have described and shown in an application filed by us of even date herewith, Serial No. 61,342. 85 From the generator A a pipe connected therewith serves to convey the gas to one or more compartments, which are closed substantially air-tight. In this pipe is inserted any suitable force-pump P, by the operation of which 90 the gas is drawn from the generator and forced through the pipes D and C into compartment E. As the generators of the usual kind are not instantaneous in their operation, it is our purpose to maintain a supply of sulfur dioxide 95 which will be always ready for immediate use.

With such object in view we employ a storage-tank or accumulator B, which is filled with sulfur dioxid under pressure obtained either from the generator A or from any other 5 source of that gas. In case a fire should occur in the compartment E the pump P is set in operation and the charge of sulfur-dioxide gas drawn from the storage-tank B. This supplies the necessary proportion of gas while 10 the generator is starting in operation. The pipe D constitutes a by-pass to the tank B, which is controlled by the valve F.

We have found that when by the above operation an atmosphere has been produced in 15 the compartment containing from ten to sixteen per cent. of sulfur dioxid and with a pressure of one or two inches of water is ample to suppress and completely extinguish burning bales of cotton into which fire has 20 eaten for several inches; but the proportion of gas may be varied and the pressure greater or less, according to circumstances.

The invention is applicable generally, of course, to the extinguishment of fires in air-tight compartments, whether on shipboard or 25 elsewhere, and it may be carried out either by the simple form of apparatus herein shown or by any other system suitable for the purpose which is capable of producing the proper atmosphere and pressure in the compartment 30 to be protected.

What we claim as our invention is—

1. The method of extinguishing fires in cotton-bales and similar combustibles, which 35 consists in confining the combustibles in air-tight

compartments, and, producing and maintaining under pressure therein, an atmosphere containing a gas which is a non-supporter of combustion.

2. The method of extinguishing fires in cotton-bales and similar combustibles, which consists in confining the combustibles in air-tight compartments, forcing into the same a mixture of air and a gas which is a non-supporter of combustion until a pressure is produced 40 therein and maintaining such pressure until the fire is extinguished.

3. The method of extinguishing fires in cotton-bales and similar combustibles, which consists in confining the combustibles in an air-tight compartment, and charging, under pressure, such compartment with a mixture of air 45 and sulfur-dioxide gas, as set forth.

4. The method of extinguishing fires in cotton-bales and similar combustibles, which consists in confining the combustibles in air-tight compartments, and, in case of fire therein, injecting into the compartments sulfur dioxid from a supply of the same stored under pressure for immediate use, and then generating 50 a further supply of sulfur dioxid and forcing it together with air into the compartments so as to produce and maintain a pressure of gas 55 therein, as set forth.
